DESIGN FOR AN AIRPLANE

David R. Davis, Los Angeles, Calif., assignor to
Manta Aircraft Corporation, Los Angeles, Calif.,
a corporation of California

Application October 28, 1940, Serial No. 96,140

Term of patent 14 years

To all whom it may concern:

Be it known that I, David R. Davis, a citizen of the United States, residing at Los Angeles, in the county of Los Angeles and State of California, have invented a new, original, and ornamental Design for an Airplane, of which the following is a specification, reference being had to the accompanying drawing, forming part thereof.

In the drawing:

Fig. 1 is a plan view of an airplane embodying my design.

Fig. 2 is a side elevational view of the airplane.

The opposite side of the airplane is substantially the same in appearance as the side illustrated in this figure.

Fig. 3 is a front elevational view of the airplane.

Fig. 4 is a view in perspective of the airplane. The characteristic feature of my design resides in the portions shown in full lines in the drawing.

I claim:

The ornamental design for an airplane, substantially as shown and described.

DAVID R. DAVIS.
